Primary Examiner — Melanie H Tung*Assistant Examiner* — Lavone D Tabor(74) *Attorney, Agent, or Firm* — Judy W. Chung(57) **CLAIM**

The ornamental design for an oral care implement accessory, as shown and described.

DESCRIPTION

FIG. 1 is a front left perspective view of an oral care implement accessory according to the new design;

FIG. 2 is a front right perspective view thereof;

FIG. 3 is a rear right perspective view thereof;

FIG. 4 is a rear left perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines and the areas within the broken lines illustrate portions of the oral care implement accessory that form no part of the claimed design.

1 Claim, 5 Drawing Sheets
